UNITED STATES PATENT OFFICE.

HENRY L. PALMER, OF BROOKLYN, NEW YORK.

DESIGN FOR THE ORNAMENTATION OF SHEET METAL.

SPECIFICATION forming part of Design No. 17,472, dated July 19, 1887.

Application filed April 14, 1887. Serial No. 231,843. Term of patent 14 years.

To all whom it may concern:

Be it known that I, HENRY L. PALMER, of Brooklyn, county of Kings, and State of New York, have invented and produced a new and original Design for the Ornamentation of Metal, of which the following is a full, clear, and exact description, reference being had to the accompanying drawings, and to the letters of reference marked thereon.

My design has relation to the ornamentation of sheet metal; and it consists of representations of raised flowers and leaves arranged in regularly-recurring order upon the surface, the intervening spaces between the patterns being filled with a multitude of fine raised points of general spherical surface disposed in distinctive straight lines, substantially as shown in the accompanying drawings.

In the drawings, Figure 1 is a plan or top view of a fragment of sheet metal ornamented with my design, and Fig. 2 represents a cross-section of the sheet so ornamented.

In both figures like letters indicate corresponding parts.

A is the piece of sheet metal, which may be of any width or length. Upon the surface of this are patterns in relief of leaves and flowers in similar groups, as shown at B B. These groups are arranged in regularly-recurring order over the entire surface, as shown, and each group is separated and distinct from every other group. The spaces between the groups

are filled with a multitude of small raised dots or projections, (represented at a a,) the effect of which is to destroy the appearance of a smooth surface between the groups B B. These dots or projections are regularly arranged or disposed in straight lines, as plainly shown. The appearance of the whole is as if the floral groups were uniformly embossed upon a uniformly or specially prepared dotted surface, lending a pleasing and not too abrupt relief to the groups and a peculiar luster to the intervening surfaces. The groups B B are semi-conventional representations of roses in different stages of expansion, each group containing but one flower.

Having now fully described my design, what I claim is—

The herein-described design for the ornamentation of sheet metal, which consists of the raised patterns of flowers and leaves arranged upon the surface in separated and regularly-recurring groups B B, and the intervening raised dots a a, uniformly disposed in straight lines and covering the entire surface between the raised floral patterns, as shown.

In testimony that I claim the foregoing I have hereunto set my hand in the presence of two witnesses.

HENRY L. PALMER.
